ANTISPLASH GUARD

Filed Dec. 10, 1928

David A. Craig Inventor

By Clarence O'Brien
Attorney

UNITED STATES PATENT OFFICE

DAVID A. CRAIG, OF LUDINGTON, MICHIGAN, ASSIGNOR OF ONE-HALF TO GEORGE H. D. SUTHERLAND, OF LUDINGTON, MICHIGAN

ANTISPLASH GUARD

Application filed December 10, 1928. Serial No. 325,044.

This invention relates to an improved safety appliance for linotype machines, and it has more specific reference to what may be conveniently entitled, an anti-splash guard.

Briefly, the invention has reference to a guard of this type which is in the form of an attachment for linotype machines, all models, and it is designed to prevent backsquirts and splashes of molten metal from the metal pot of the linotype machine, as well as drips from air vents from contacting and splashing against the legs of the operator.

An important object is to provide a device of this kind which insures satisfactory results, and which is highly advantageous in that it is capable of being attached to existing parts of the machine without requiring alterations, or without interfering with efficient operation of said parts.

The principal novelty is predicated upon production of a device which is economical, efficient in performance, and capable of fulfilling the requirements of an attachment of this class in a highly satisfactory manner.

In the drawing:

Figure 1 is a fragmentary elevational view of a portion of a conventional linotype machine showing the attachment in operative position thereon.

Figure 2 is a perspective view of the attachment per se.

In the drawings the reference character W designates the mold wheel, and F designates a portion of the frame on which the starting and stopping lever L is pivotally mounted. At this point there is an existing bolt B which in accordance with the present invention is given the additional function of holding the guard 3 in place. This guard as shown better in Figure 2 comprises a longitudinally bowed or arcuate top portion 4 having a flange 5 along one longitudinal edge, an intermediate portion 6 disposed at a substantially obtuse angle to the top portion 4 and a depending apron 7, flaring outwardly at substantial right angles to the central portion 6. The portion 6 is equipped with notches to accommodate parts of the

machine in order that the attachment may assume the proper position without interfering with the operation of the existing parts of the machine. On the under side of the portion 6 is a centralized flange 8 which is shaped to rest on the frame and to be connected with the bolt B as seen in Figure 1. The attachment thus in place cooperates with the peripheral toothed portion of the wheel, in which position it is properly located to protect an operator from contact with overflowing or splashed hot metal from the metal pot (not shown).

The attachment is characterized by unusual simplicity in construction and design, and has been found to operate satisfactorily in every respect.

It is believed that persons familiar with linotype machines and the danger attached thereto from splashing of molten metal, will be able to appreciate the value of the attachment and will obtain a clear understanding of the construction and method of attachment. Consequently a more lengthy description is regarded unnecessary.

Minor changes in size, shape and arrangement and material coming within the field of the invention claimed may be resorted to in actual practice if desired.

Having thus described the invention, what I claim as new and desire to secure by Letters Patent is:—

In a structure of the class described, in combination, a linotype machine including a frame having a mounting bracket thereon, a starting and stopping lever pivotally mounted on said bracket, and a mold wheel on the frame in close proximity to said bracket, and an anti-splash guard mounted on said bracket for cooperation with the periphery of the mold wheel, said guard being adapted to protect the hands and legs of the operator against injury and burns from overflowing and splashing molten metal from the metal pot on said machine and comprising a splash plate including an upper longitudinally bowed portion having a longitudinal flange on one edge, an intermediate portion disposed at a substantial obtuse angle to said

upper portion and provided on its under-
side with an apertured attaching flange se-
cured to said bracket, and a depending apron
disposed at right angles to said intermediate
portion and extending below said bracket.

In testimony whereof I affix my signature.

DAVID A. CRAIG.
